DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

7 Sheets Drawing. 20 Pages Specification

PRIOR ART

A multiphase control program nucleus loading method reduces the amount of real storage required for initialization by dividing the initialization process into phases. Each phase operating in sequence controls the loading of a different portion of the control program nucleus into real or virtual storage. Only those portions of the control program nucleus required for performing the initialization process at a given time are loaded into real storage. After a function is completed, the obsoleted portion of the nucleus is overlaid with another portion of the nucleus which will perform a next series of functions which are required. By using a time dimensional scatter loading technique for loading portions of the control program nucleus only when they are required for their function, the amount of real storage required for nucleus initialization is significantly reduced; and pageable portions of the control program nucleus not required for initialization are loaded directly into virtual storage.
